UNITED STATES PATENT OFFICE.

EMMA M. REQUA, OF NEW YORK, N. Y.

DESIGN FOR A BADGE.

SPECIFICATION forming part of Design No. 11,981, dated October 19, 1880.

Application filed March 15, 1880. Term of patent 7 years.

To all whom it may concern:

Be it known that I, EMMA M. REQUA, a citizen of the United States, residing in the city, county, and State of New York, have invented and produced a new and original Design for a Badge, of which the following is a specification, reference being had to the accompanying drawing, forming part thereof.

My design consists, essentially, of a globe 10 freely suspended from an ornamental pin above it, and preferably bearing any suitable inscription—such, for instance, as “World’s Fair, 1883”—or it may bear some other inscription commemorative of some important event.

15 In the accompanying drawing illustrating my invention, A indicates a pin in the form of a spread-eagle, from which depends a tricolored ribbon pendant, B, having attached to its lower end a geographical globe, C.

20 The foregoing is the exact design I prefer

to make; but it is obvious that the essence of my invention is a globe freely depending from a pin—that is to say, not within and surrounded by an annular or other shaped pin or frame. The pin may be plain or of any other figure than that shown, and the pendant B 25 may be of metal or of any other material than tricolored ribbon, without departing essentially from the substance of my invention.

I claim—

30 The design for a badge herein described and shown, which consists of a pin, A, a pendant, B, and a freely depending globe, C, the pendant and globe being wholly beneath the pin, as described, and shown in the accompanying 35 illustration.

EMMA M. REQUA.
